CLAIM

The ornamental design for a coalescer bracket, as shown and
described.

DESCRIPTION

FIG. 1 is a perspective view of a coalescer bracket depicting
a first embodiment of a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line portion of the figure drawings is included to
show unclaimed subject matter only and forms no part of the
claimed design.
